JEROME R. L. GREEN, OF SACRAMENTO, CALIFORNIA

HYBRID ELECTRICAL SWITCH

Application filed March 3, 1927. Serial No. 172,450.

This invention relates to certain new and useful improvements in electric switches, either of single or multiple phase type and bearing particular reference to an electric switch wherein fuses are employed, has for its primary object to provide a switch wherein that part of the switch which bridges the spaced contacts or terminals embodies a fuse carried by a swingingly mounted insulating plate so that when the plate is moved to permit access to the fuses for replacement or the like, the circuit is broken and handling of the fuses may be accomplished without subjecting one to injury.

With the above and other objects in view that will become apparent as the nature of the invention is better understood, the same consists in the novel form, combination and arrangement of parts and in the details of construction hereinafter more fully described, shown in the accompanying drawings and claimed.

In the drawings wherein like reference characters indicate corresponding parts throughout the several views,

Figure 1 is a front elevational view of a switch box with the hinged cover wall thereof partly broken away to show the insulating plate hingedly supported within the casing with cartridge fuses upon the inner face thereof that bridge the contacts;

Figure 2 is a front elevational view of the switch box with the cover in open position, the insulating plate being moved upon its hinged mounting for displacing the cartridge fuses from engagement with the contacts;

Figure 3 is a vertical cross-sectional view taken on line 3—3 of Figure 1;

Figure 4 is a cross-sectional view, similar to Figure 3, showing the switch in its open position with the cartridge fuse functioning as a switch blade;

Figure 5 is a top plan view of the insulating plate that carries the cartridge fuses;

Figure 6 is a vertical cross-sectional view of the switch box showing the screw plug fuses carried by and movable with the plate that carries a switch blade; and

Figure 7 is a perspective view of an angle limit strip for one end of the cartridge fuse.

The switch box may be of any preferred design and the same is illustrated as being of rectangular formation and comprising a rear wall 1, side wall 2, a top wall 3, a bottom wall 4 and a front door 5 that is hinged at 6 to the lower forward edge of the bottom wall 4. A sliding catch 7 carried by the free swinging upper edge of the door 5 engages a keeper carried by the top wall 3.

A comparatively large insulating plate 8 is secured by the fastening devices 9 to the inner face of the rear wall 1 of the switch box and a plurality of switch terminals 10 secured to the upper end of the insulating plate 8 are aligned with the switch terminals 11 carried by the lower end of the insulating plate, the switch terminals 10 and 11 as shown in Figures 2 to 4 being of the spring finger type and being in circuit with a source of electric energy with the circuit broken between the respectively aligned upper and lower terminals 10 and 11.

The primary object of the invention being to bridge the aligned switch terminals 10 and 11 by a fuse carried by a swingingly mounted insulated plate so that in order to attain access to the fuses for repair, replacement or the like, it is first necessary to move the swingingly mounted insulating plate to displace the fuses from the switch terminals, and to accomplish this result, there is provided a pivotally supported frame comprising bearing ends 12 and 13 journaled in bearing blocks 14 set into the side walls 2 of the switch box adjacent the lower ends thereof, the inner ends of the bearing portions 12 and 13 being right-angularly extending arms 15 connected by a cross arm 16. The outer end of the bearing 13 carries an operating handle 17 aligned with the adjacent arm 15 so that when the handle 17 is moved, the frame structure within the switch box comprising the arms 15 and 16 are moved in similar directions. The arms 15 adjacent the bearings 12 and 13 are connected by the brace bar 18 that is made integral or rigid therewith.

The pivotally mounted frame within the switch box carries the insulating plate 19 upon which the fuses for bridging the switch terminals 10 and 11 are mounted. The in-

sulating plate 19 is secured to the frame by the fastening devices 20 extending through the insulating plate and the brace bar 18 while staples 21 inclosing the cross arm 16 pass through the insulating plate 19 and receive nuts 22 upon the inner threaded end thereof. As shown more clearly in Figures 4 and 5, spaced bearing blocks 23 of insulating material are secured to the inner faces of the insulating plate 19 for supporting the fuse 24 that is of the cartridge type, the opposite ends 24^a of the cartridge fuse being connected with the circuit fuse within the cartridge. The cartridge fuse is removably supported on the bearing blocks 23 by the hook staple 25 having the hook end thereof overlying the fuse with the threaded end of the staple passing through the insulating plate 19 to receive the thumb nuts 26. An angle limit strip 23^a is secured to the insulation plate 19 beneath the bearing blocks 23 at one side of the plate 19 and is slotted at its angle end as at 23^b to accommodate the projecting blade of a cartridge fuse having a blade terminal. The angle end of the strip also acts as a limit stop and positioning device for a cartridge fuse.

The operation of the device will be readily understood from an inspection of Figures 3 and 4, the switch when in its closed position as illustrated in Figure 3 having the contact ends 24^a of the cartridge fuse engaged by the spring fingers of the aligned switch terminals 10 and 11. As shown in Figure 3, the fuse 24 is interposed between the insulating plate 8 rigidly carried by the rear wall of the switch box and the pivotally mounted insulating plate 19 carried by the movable frame. It will be seen that access to the fuses is impossible when the circuit is closed and in order to reach the fuses, the insulating plate 19 must be shifted to the position shown in Figure 4 by operating the handle 17 and frame carried thereby that supports the insulating plate 19 and in so doing, the fuse 24 is displaced from the switch terminals 10 and 11 and free handling of the fuses for repair, replacement or the like is readily accomplished without subjecting one to injury. With a switch of this character, fire hazards are practically eliminated by reason of the fact that the old type of three-pole switch had twelve contacts whereas the present disclosure has but six contacts, this reduction of contacts lessens the chances of arcs at the contacts. It is also immaterial as to which terminals the lead in wires are connected to as wrong wiring will not affect operation of the switch.

The same objects are accomplished in the form of the invention shown in Figure 6, wherein a fuse of the screw plug type is employed, the insulating plate 8^a carried by the rear wall 1^a of the switch box having switch terminals 10^a and 11^a that are engaged by

switch blades 27 carried by the insulating plate 19^a. The insulating plate 19^a is carried by the pivotally mounted frame, the same as illustrated in Figure 1. The switch blades 27 are in communication with the socket 28 formed in the insulating plate 19^a, and the spaced switch blades 27 are placed into communication when the plug fuse 29 is screwed into the socket 28. The head of the fuse 29 being interposed between the insulating plates 8^a and 19^a, it will be understood that the insulating plate 19^a must be moved upon its pivotally mounted supporting frame to gain access to the head of the fuse and in so doing, the switch blades 27 are displaced from engagement with the switch terminals 10^a and 11^a.

While there is herein shown and described the preferred embodiment of the invention, it is nevertheless to be understood that minor changes may be made therein without departing from the spirit and scope of the invention as claimed.

What I claim as new is:—

1. An electric switch comprising a box 90 having a front door, a vertical insulating plate fixed in the back of the box, conductor terminal clips mounted on said plate, a second insulating plate hingedly mounted in the box to swing independently of the door upwardly into and downwardly substantially out of the box through the front of the latter, fuses carried by said second plate and having contacts engageable with said terminal clips when said second plate is swung upwardly 100 into the box, and manually operable means to swing said second plate into and out of the box, said second plate being adapted to assume a substantially horizontal position when swung outwardly and downwardly to 105 expose the fuses and to disengage their contracts from the terminal clips.

2. An electric switch comprising a box having a front door, a vertical insulating plate fixed in the back of the box, conductor terminal clips mounted on said plate, a second insulating plate hingedly mounted in the box to swing independently of the door upwardly into and downwardly substantially 110 out of the box through the front of the latter, fuses carried by said second plate and having contacts engageable with said terminal clips when said second plate is swung upwardly into the box, a crank frame to which the second plate is secured, said crank frame having aligned horizontal shaft members disposed adjacent the lower edge of said second plate and journaled in the sides of the box, and an operating handle rigid with one of 115 said shaft members and arranged outwardly 120 of one side of the box.

3. An electric switch comprising a box having a front door hinged at its lower end for swinging downwardly to open position, a vertical insulating plate fixed in the back of 130

the box, conductor terminal clips mounted on said plate, a second insulating plate hinged at its lower end within the bottom of the box to swing independently of the door upwardly into and downwardly substantially out of the box, fuses carried by said second plate and having contacts engageable with said terminal clips when said second plate is swung upwardly into the box, and manually operable means to swing said second plate into and out of the box, said second plate being adapted to assume a substantially horizontal position overlying the door when swung outwardly and downwardly to expose the fuses and disengage their contacts from the terminal clips.

4. In a switch of the character described, the combination with an insulated plate upon which are mounted fuses, and a casing containing terminal contacts for the engagement of said fuses, of an operating lever consisting of a U-shaped bar comprising side arms, a connecting section and a crank arm, said lever being pivotally connected to said casing, and attached to the insulated plate above its horizontal medial line, whereby the insulated plate may be swung downwardly to a horizontal position outside the casing.

In testimony whereof I affix my signature.
